UNITED STATES PATENT OFFICE.

JOHN CHANTRELL, OF BRIDGEPORT, CONNECTICUT.

COIN-HOLDER.

SPECIFICATION forming part of Letters Patent No. 245,787, dated August 16, 1881.

Application filed January 7, 1881. (Model.)

To all whom it may concern:

Be it known that I, JOHN CHANTRELL, of Bridgeport, in the county of Fairfield and State of Connecticut, have invented a new and useful Improvement in Coin-Holders, of which the following is a specification.

Figure 1 is a perspective view of my improvement, illustrating its use. Fig. 2 is a rear elevation of the holder. Fig. 3 is a sectional plan view of the same, taken through the line $x-x$, Fig. 2.

Similar letters of reference indicate corresponding parts.

The object of this invention is to hold rolls of coin in such a manner that the coins can be readily seen and counted and conveniently handled.

The invention consists in the combination, with the back piece and the side loops, of a band to pass around the roll of coins directly opposite the said back piece, so that the coins will be held at four points of their circumferences; and also in constructing the back piece with long eyes along the end parts of its side edges and parallel with its length, to receive the inwardly-bent end parts of the arms of the side loops to adapt the said end parts to operate as torsion-springs for holding the said loops against the roll of coins, as will be hereinafter fully described.

A is the back piece, which is made of a length equal to the height of a roll of the desired number of coins.

B are two wire loops, which are made of elastic wire, and with their middle parts straight and of a length equal to the length of the back piece, A. The arms of the loops B have a slight lateral curve, as shown in Figs. 1 and 3, and their end parts are bent inward or toward each other at right angles, to pass through eyes C, formed upon the side edges of the end parts of the back piece, A, and parallel with its length by turning the said edges back upon themselves, as shown in Figs. 2 and 3. The

ends of the arms of the loops B are bent across the back piece, A, as shown in Figs. 2 and 3. By this construction the parts of the wires B that pass through the eyes C act as torsion-

springs in holding the side loops against the roll of coins, and allowing the said loops to be drawn back for inserting and removing the coins. This construction also allows the wires B to be of such a size and stiffness as will hold the coins securely. The arms of the loops B are made of such a length that the straight middle parts of the said loops will rest against the edges of the coins at points at a distance from the back piece, A, about equal to one-quarter of the circumferences of the said coins.

D is a loop or band, which may be a flat strip of metal or a wire, the middle part of which rests against the edges of the coins directly opposite the back piece, A. The arms of the band D rest against the outer sides of the end coins of the roll, and their ends are bent inward along the outer side of the end parts of the back piece, A, where they are secured in place by the eyes C, or by solder or other suitable means.

By this construction the coins are held at four points of their circumferences, and will thus be held securely, while either of the loops B can be easily sprung back so far as to allow the roll of coins to be put into the holder and taken out.

Having thus fully described my invention, I claim as new and desire to secure by Letters Patent—

1. In a coin-holder, the combination, with the back piece, A, and the wire loops B, of the band D, substantially as herein shown and described, whereby the coins will be held securely in place, as set forth.

2. In a coin-holder, the eyes C, formed upon the side edges of the back piece, A, and parallel with its length, to receive the inwardly-bent end parts of the arms of the wire loops B, substantially as herein shown and described, to adapt the said end parts to operate as torsion-springs for holding the said loops in place, as set forth.

JOHN CHANTRELL.
